UNITED STATES PATENT OFFICE.

GERTRUDE G. CONDON, OF OAKLAND, CALIFORNIA, ASSIGNOR TO THE HOOVER COMPANY, A CORPORATION OF OHIO.

HAND AND FINGER PROTECTOR.

Application filed August 24, 1925, Serial No. 52,142. Renewed February 26, 1927.

My present invention relates to hand and finger protecting devices, and more particularly to such a device for the handle of vacuum-cleaner dust-bags.

5 In practically every make of vacuum cleaners provided with a bag for collecting the dust, the bag during the machine's operation is connected with its top to the operating handle of the machine, and in the type 10 commonly known as the "Hoover", the dust bag has resilient connection with the closed end of the bag by means of a handle comprising a pair of tapering, pivotally-connected, spring-actuated and self-closing 15 members so that, whether the operating handle is raised or lowered, the bag is automatically held in the proper position.

When the bag has been removed from the machine for emptying it after the cleaning 20 operation, the operator steps on the metallic ring member by which the bag is secured to the machine, and by holding the bag at the top in a tensely stretched relation and gently shaking it, removes the dust. During this 25 process the members of the bag handle are caused to move pivotally back and forth scissor-like while the operator grips the handle with the hand. Thus, having had the hand or fingers pinched and some times 30 painfully hurt, many operators prefer to engage or fold the top of the cloth bag over the handle in order to avoid injury to their hands and fingers. Again, continual folding 35 of the bag is detrimental thereto, and causes a leak therein so that the bag soon becomes inoperative and must be repaired.

It is the purpose of my invention to provide a means adapted to be attached to a dust-bag handle for vacuum cleaners of the 40 "Hoover" type, or the like, for preventing a person's hand and fingers from being pinched by the members when the handle is gripped and operated so as to cause pivotal movement back and forth of the handle 45 members to accomplish a bellow-like movement of the bag for the removal of the dust therein and out through the bottom or mouth of the bag.

In the accompanying drawings, which illustrate the invention, Figure 1 is a side elevation of a dust bag provided with a metallic handle for a vacuum cleaner of the "Hoover" type and a hand and finger protector of my invention attached thereto and 55 depending therefrom;

Fig. 2 is a transverse mid-section of the handle and my protector attached thereto in the grip of a person's hand, and shows how the protector folds over the sides of the handle and thereby prevents pinching of the 60 hand and fingers by the members of the handle;

Fig. 3 is a side elevation of the handle when open to hold the bag tensely stretched, and my attached protector is shown in snug 65 engagement with the handle as if held thereto by the hand; the upper corners of the bag are shown and the means for their attachment to the handle;

Fig. 4 is a perspective view of a woman 70 as she grips the bag in the process of emptying it after the cleaning operation; and

Fig. 5 is a plan of my protector in full lines and of the handle in dot-and-dash lines, showing the tapering members of the 75 handle and the width of the protector as compared with that of the handle, and also how the loops on the protector hold it in virtually central relation to the handle.

In Fig. 1 is shown a dust bag 6 for a 80 vacuum cleaner of the "Hoover" type. The bag at its open end is provided with the usual ring member 7 for connection with a vacuum cleaner and at its closed end is provided with hooks 8 for attaching it to the 85 bag handle or holder 9. The latter comprises two tapering, pivotally connected, spring-actuated, self-closing and similarly shaped members 10. The members overlap each other and have their overlapping portions 90 11 provided with terminal eyes 12, adapted to receive therein the hooks of the strap by which the handle or holder is attached to the operating handle of the cleaner, these latter parts not being necessary for the understanding 95 of my invention are therefore not shown.

My protector 14 comprises an element 15 of any suitable flexible material, such as cloth, for example, and is preferably made of more than one thickness of the cloth and 100 sewed along its edges, as is shown at 16 in Fig. 5, so as to form a pliant pad-like member adapted to fold over the edges of the handle 9. At each end of the element 15 I provide a loop 17, which may be made of 105 the same material as the element itself or other textile fabric, but is preferably made of wire and sewed to the element, as at 18 in Fig. 5. The loops 17 fit over the tapering members 10 of the handle so that when the 110

2
element 15 is attached by them to the handle, receives the pinches the operator otherwise 30 would have suffered.

In order to attach my protector to the handle of the dust bag 6, one loop 17 is slipped over the end of one member 10; the members are then moved pivotally so as to permit the other loop to be slipped over the end of the other member 10, and the spring-
10 actuated members are thereafter allowed to close to normal position, thus securing the protector to the handle at the underside thereof.

When it is desired to empty the dust bag; 15 the operator detaches the bag from the machine and grips the handle of the bag, and spreading a paper or other protective covering upon the floor, steps upon the outwardly projecting ears of the ring member 7, and by 20 gently shaking the bag removes the dust from the bag to the protective floor covering. During this operation the members 10 will be moved pivotally back and forth to cause the bag to bellow to dislodge the dirt, but no 25 injury can be caused to the operator's hand or fingers by such pivotal movement on account of my protector, which folds itself over the members of the handle and follows their pivotal movement so that the protector

My protector having been attached to the handle of the dust bag may be left there as a permanent part of the handle.

Having thus described my invention and being desirous of securing Letters Patent of the United States therefor, I claim as new the following:

40 A hand and finger protector comprising an element made of a flexible material; and a loop at each end of the element, each of said loops being adapted to engage one member of a vacuum-cleaner dust-bag handle comprising two pivotally-connected and self-closing members, so that the element is 45 thereby held in a virtually central relation to the handle pivot, said element being of greater width than said members so that it is adapted to fold over the members and to follow their pivotal movement in order to 50 prevent a person's hand and fingers from being pinched by the members when the handle is gripped and operated so as to cause pivotal movement back and forth of said members.

55 In testimony whereof, I affix my signature.

GERTRUDE G. CONDON.
